FOOT MEASURING DEVICE

Application filed April 13, 1928. Serial No. 269,686.

The object of the invention is to provide a foot measuring device by which a foot is centered preliminary to measurement along a line passing through the longitudinal centre 5 of the foot, by which the foot may then be accurately measured as to length and width, and indication of such measurement shown in terms of a proper sized shoe for such measurement.

10 The invention can best be seen and understood by reference to the drawings in which—

Figure 1 is a plan of the device.

Fig. 2 is a plan of the under side of the device.

15 Fig. 3 is a section on the line 3—3 of Fig. 1.

Fig. 4 is a section on the line 4—4 of Fig. 1, and

Fig. 5 is a section on the line 5—5 of Fig. 1.

20 Referring to the drawings:—

1 represents a plate having feet 2 all combining to form a footrest. Arranged to be movable over the top surface of this plate are two sets of stops 3, 4; 5, 6. The stops 3 and 4 are arranged to be adjustably movable toward and away from one another over the face of the plate or footrest on a line which represents, or is assumed to represent the true longitudinal centre of the foot to be measured by the device. When a foot to be measured 25 is placed upon the plate 1 between the stops 3 and 4, the stop 3 is movable to engage the extremity of the heel while the stop 4 is movable to engage the extremity of the toe. The distance between the stops then determines the length of the foot. The heel stop 3 functions both as a stop and a heel-centering member, the stop being made V-shaped so that when the heel is contained therein it will be centered on the line of travel of the stops 3 and 4 without possibility of lateral displacement.

30 The stops 5 and 6 are arranged to be adjustably movable toward and away from one another over the face of the plate on a line at right angles to the line of travel of the heel and toe stops 3 and 4. The stops 5 and 6 are each positioned an equal distance away from said line and their relative positioning is also such that their line of travel will pass through the ball of the foot to be measured when en-

gaged by the heel and toe stops so that the stops 5 and 6 will engage the opposite sides of a standard foot or last standard of foot adjacent its ball or the widest part of the foot where a lateral measurement is desired. In 35 other words, the heel and toe stops 3 and 4 are positioned to bear such relation to the side stops 5 and 6 that in the standard foot or last standard of foot the side stops will be in position to properly engage the sides of the foot 40 at the ball when the heel and toe stops are engaging the opposite ends of the foot, and this relation is maintained whatever the adjusted position of the heel and toe stops may 45 be. To put the matter in another way, the 50 side stops are so located with relation to the heel and toe stops that the side stops will engage that portion of the ball of the foot being measured at a point corresponding with the ball portion of a standard foot or last 55 standard of foot if it were inserted in place of the foot being measured in the measuring device.

Thus positioned and arranged the side 60 stops 5 and 6 will co-operate with the heel 65 stop 3 to form a three-point contact for the foot so that when the foot is in proper engagement with these stops they will operate to centre the foot longitudinally so that the 70 true longitudinal line between the heel and toe stops or line along which they are movable will correspond with the longitudinal 75 centre of the foot.

The heel and toe stops are moved toward 80 and away from one another by means of a 85 screw 7 arranged beneath the plate 1 and turning in bearings 8 fixed to the under side of the plate. The screw is provided with right and left threaded portions 9 and 10, 90 respectively, by which the respective stops 3 and 4 may be moved simultaneously an equal amount in reverse directions toward or away 95 from one another depending as the screw is turned in one direction or the other. The screw projects beyond the end of the plate 1 or footrest and is turned by a crank 11 arranged upon its end. Connection between the stops 3 and 4 and the respective threaded portions of the screw is obtained through 100 slots 12 and 13, respectively, cut in the

plate 1. These slots are so cut that the central longitudinal line of each of the slots will lie within the line along which the stops 3 and 4 are movable. The stops 3 and 4 are each carried by a base piece 14 which slides upon the top surface of the plate 1 as the stops are moved, the base piece for the respective stops being wider than the slots in the plate and overlapping the plate adjacent the opposite sides of the slots. Connected with the base piece 14 of the heel stop and extending down through the adjacent slot 12 in the plate to be slidable therein is a slide 15. To this slide is secured a nut 15' arranged on the threaded portion 9 of the screw. Connected to the base piece 14 of the toe stop is a slide 16 arranged within and extending down through the slot 13 in the plate and provided with a nut-forming extension 16' arranged on the threaded portion 10 of the screw. Both the slides 15 and 16 to which the heel and toe stops are connected have a snug sliding fit within the slots within which they are contained and the opposite sides of the slots will accordingly function as guides for the respective slides and through them will cause the stops 5 and 6 as they are moved by the turning of the screw to hold to a properly centered line of travel. Secured to the base piece 14 of the stop 4 is a pointer 17. This pointer extends at right angles to the line of travel of the stops 3 and 4 and the end thereof indicates certain spaced lines 18 on a plate 19 secured to the plate 1 and with which lines 18 are associated numerals 1 to 13, inclusive, which correspond with the different sizes of shoes in point of length. In other words, as a foot is measured the adjusted position of the stop 4 will through the pointer indicate the proper size of shoe as to length, the different sizes being determined by the changed position of the stop 4. The stops 5 and 6 are moved toward and away from one another by means of a screw 20 arranged beneath the plate 1 and turning in bearings 21 fixed to the under side of the plate. The screw 20 is provided with right and left threaded portions 22, 23 by which the respective stops 5 and 6 will be moved simultaneously in equal amount in reverse directions toward or away from one another depending as the screw 20 is turned in one direction or the other. The screw 20 projects beyond the side of the plate or footrest and is turned by a hand wheel 24 arranged on its end. Connection between the stops 5 and 6 and the respective threaded portions of the screw are obtained through slots 25, 26, respectively, cut in the plate 1. These slots are cut to lie in alignment with one another with the central line thereof at right angles to the line of travel of the stops 3 and 4. The stops 5 and 6 are each carried by a base piece 27 which slides upon the top surface of the

plate 1 as the stops are moved, the base pieces for the respective stops being wider than the slots in the plate and overlapping the plate adjacent the opposite sides of the slots. Connecting with the base piece 27 of the respective stops 5 and 6 and extending through the slots 25, 26, respectively, in the plate 1 are slides 28, the slide connection for the stop 5 is provided with a nut-forming extension 29 arranged on the threaded portion 22 of the screw 20, and the slide connection for the stop 6 is provided with a nut-forming extension 30 arranged on the threaded portion 23 of the same screw. The slides for the respective stops 5 and 6 slide with a loose fit in the respective slots along which they are movable and the opposite sides of the slots will accordingly function as guides for the respective slides and through them will cause the stops 5 and 6 as they are moved by the turning of the screw 20 to move along a line at right angles to the line of travel of the stops 3 and 4. As the stops 5 and 6 are moved simultaneously inward and outward along their line of travel they will maintain at all times an equal distance from the line of travel of the stops 3 and 4 and accordingly drawing against the sides of a foot placed upon the plate with the heel bearing against and centered by the stop 3 as aforesaid will through their drawing contact against the side of the foot cause it to be truly centered with relation to the line of travel of the stops 3 and 4, after which further manipulation of the stops 5 and 6 will cause them to bear lightly against the opposite sides of the foot at the ball so that the distance between the stops will correspond with the width of the foot.

The proper width of shoe for any determinate foot measurement as to width, taking into consideration the size of the shoe as to length, is indicated as follows: Fixed in the top of the plate 1 is a circular dial 32. This dial is provided on its top surface with spaced lines or graduations 33 with which are associated the commonly employed notations of shoe width varying from 4A to H, inclusive. Turning within this outer dial is a circular indicator plate 34. This plate along its edge is provided with spaced radial lines or graduations 35, the spacing of these lines or graduations corresponding substantially with the spacing of the lines or graduations 33 on the outer circular dial 32 so that when the indicator plate 34 is turned to a determinate position the graduations thereon and on the dial, respectively, will coincide. Associated with the spaced lines or graduations 35 on the indicator plate are notations of shoe lengths varying from 1 to 13, inclusive, these indications corresponding with the commonly employed indications of shoe lengths. The indicator plate 34 is fixed to a shaft 36 which extends through the plate 1

acting as a bearing, through an auxiliary plate 37 secured to the under side of the plate 1 with extension beyond this plate. Secured to the end of the shaft thus projecting is a sleeve 38 carrying on its outer end a gear 39. The inner end of the sleeve 38 bears against the under side of the plate 37 and thereby operates to hold the indicator plate 34 in place on the plate 1 but with permitted turning with relation to the top surface of the plate. Meshing with the gear 39 is a gear 40 the hub of which is arranged to turn on a shaft 41 fixed to and projecting downward from the auxiliary plate 37, the hub of the gear 40 being retained by a nut 42 on the lower end of the shaft. Turning also on the shaft 41 and fixed to the hub of the gear 40 is a worm gear 43 which is turned by a worm 44 arranged upon the body of the screw 20. In other words, the circular plate 34 is turned through the chain of mechanism just recited by the turning of the screw 20 and will be turned in a clockwise or anticlockwise direction as the screw 20 is similarly turned by its hand wheel 24.

The graduations on the circular dial or scale 32 indicating width of shoe occupy a spaced relation to one another commensurate with determinate changed positions of the side stops 5 and 6; also the pitch of the screw 20 which operates the side stops is such that the side stops will be moved with a determinate degree of movement so that changed adjusted positions thereof will be commensurate with the graduations on the scale 32 indicating width of shoe. In other words, the distance between the graduations on the scale 32 is substantially commensurate with the changed distance between the stops 5 and 6 as they are adjusted to measure a single size. The graduations 1 to 13, inclusive, indicating size of shoe as to length on the indicator plate 34 are arranged in positions commensurate with determinate adjusted positions of the side stops 5 and 6 and the spaces between these graduations are substantially equal to the spaces between the graduations on the scale 32 indicating width of shoe. The indicator 34 co-operates with the scale 32 in such manner that any one of its graduations, as the indicator is moved, will traverse all the graduations on the scale 32 and coincide with any one of these graduations for purposes of indication. The operation of the mechanism for moving the indicator 34 is such that as the side stops are moved for varying their adjusted position the indicator will be moved in a direction determinate with the direction of movement of the side stops and in such an amount that the indicator will move a distance equal to the space between the graduations on the scale 32 indicating width as the side stops are moved in an amount equal to a single shoe width.

The disposition, order and arrangement of the parts being thus obtained, the proper width of shoe for any determinate foot measurement, taking into consideration the size of the shoe as to length, will be determined by the turning of the screw 20. For example, assuming a foot being measured requires a No. 7 shoe in length as indicated by the pointer 17 with relation to the graduations and numerical indications of size appearing on the plate 19, the foot having been measured for length, is measured for width by the turning of the screw 20 in one direction or the other for moving the stops 5 and 6 into engagement with the sides of the foot at the ball. By now referring to the scale 32 and the indicator plate 34 which turns with relation to the scale 32 the proper width of shoe is indicated for the measured foot which requires a No. 7 shoe as to length, by first noting the line upon the indicator plate 34 with which is associated the numeral 7 and then noting where this line points on the scale 32, the place of its pointing indicating the proper width of shoe. It may point to a line or graduation with which is associated the letter C, whereupon it will be known that this particular foot requiring a No. 7 shoe in length, will require a No. C in width. In this way the proper width of shoe is ascertained for any measured foot which requires any determinate size of shoe as to length.

The operation of using the device is as follows: All the stops 3, 4; 5, 6 are first turned out so that the foot to be measured placed upon the plate 1 will fit freely between all the stops. The heel is then snugly inserted in the stop 3. The heel stop 3 is then moved inward until the side stops 5 and 6 lie on opposite sides of the ball of the foot. As the heel stop 3 is moved inward the toe stop will also be moved inward to a point in substantial contact with the toe end of the foot. The side stops 5 and 6 are then moved inward by the turning of the screw 20 in a clockwise direction until both bear snugly against the opposite sides of the foot at the ball. This acts to centre the foot upon the plate 1, the heel stop 3 together with the two side stops 5 and 6 then forming a three-point contact by which the foot is centered along a line passing through its longitudinal centre and which line is the line of travel of the stops 3 and 4. The stops 3 and 4 are then moved inward so that they will contact with the opposite ends of the foot, the stop 3 with the heel and the stop 4 with the toe. The then position of the end stops determines the precise length of the foot and the size of the shoe as to length is determined for such measured length of the foot by indication of the pointer 17 with relation to the size indications appearing on the plate 19. The side stops 5 and 6 are then loosened and weight is brought to bear upon the foot so that its full

- width dimension is obtainable. The stops 5 and 6 are then moved so as to lightly bear against the opposite sides of the foot at the ball by the turning of the screw 20, which turned position of the screw 20 and adjusted positions of the stops 5 and 6 then determine the proper width of shoe for the measured foot as indicated by the indicator 34 on the scale 32 in the manner previously explained.
- 10 Inasmuch as the side stops are so located relatively to the heel and toe stops that they will properly engage the ball portion of a standard foot or last standard of foot when the heel and toe stops are engaging its opposite ends, ensures that any foot being measured in the device will be given a shoe properly corresponding with the measurement taken inasmuch as shoes have a certain standard of form and the measurement will correspond with such standard.
- 15 Having thus fully described my invention, I claim and desire to secure by Letters Patent of the United States:—

1. In a foot measuring device, the combination comprising a foot rest, spaced heel and toe stops for measuring the length of a foot movable toward and away from one another to any determinate adjusted position along a common line of travel extending substantially through the longitudinal centre of a foot interposed between said stops and resting upon the foot rest, side stops for measuring the width of a foot, said side stops being located relatively to said heel and toe stops whereby the side stops will engage that portion of the ball of the foot being measured at a point corresponding with the ball portion of a standard foot or last standard of foot were it inserted in place of the foot being measured in the measuring device, and means for simultaneously moving the heel and toe stops each in an equal amount toward or away from one another whereby the relation of said side stops thereto will be maintained.

2. In a foot measuring device, the combination comprising a foot rest, spaced heel and toe stops for measuring the length of a foot and movable toward and away from one another to any determinate adjusted position along a common line of travel extending substantially through the longitudinal centre of a foot interposed between said stops and resting upon the foot rest, side stops for measuring the width of a foot movable toward and away from one another to any determinate adjusted position along a common line of travel extending at right angles to the line of travel of the heel and toe stops, said side stops being located relatively to said heel and toe stops whereby the side stops will engage that portion of the ball of the foot being measured at a point corresponding to the ball portion of a standard foot or last standard of foot were it inserted in place of the foot

being measured in the measuring device, means for simultaneously moving the side stops each in an equal amount toward or away from one another, and means for simultaneously moving the heel and toe stops each in an equal amount toward or away from one another whereby the relation of said side stops thereto will be maintained.

3. In a foot measuring device, the combination comprising a foot rest, spaced heel and toe stops movable toward and away from one another to any determinate adjusted position along a common line of travel extending substantially through the longitudinal centre of a foot interposed between said stops and resting upon the foot rest, said heel stop being formed also whereby it will function as a centering device for the heel portion of the foot interposed between said stops with relation to their line of travel, side stops each arranged equidistant from the line of travel of the heel and toe stops and movable toward and away from one another to any determinate adjusted position along a common line of travel extending at right angles to the line of travel of the heel and toe stops, said side stops being located relatively to said heel and toe stops whereby the side stops will engage that portion of the ball of a foot being measured at a point corresponding with the ball portion of a standard foot or last standard of foot were it inserted in place of the foot being measured in the measuring device, said heel stop and said side stops co-operating also to form a three-point contact whereby a foot interposed between the heel and toe stops and centered in part by the heel stop will be further centered along the line of travel of the heel and toe stops as the side stops are moved into engagement with the opposite sides of the foot, means for simultaneously moving the side stops each in an equal amount toward or away from one another, and means for simultaneously moving the heel and toe stops in an equal amount toward or away from one another whereby the relation of the side stops thereto will be maintained.

4. In a foot-measuring device, the combination comprising side stops movable toward and away from one another for measuring the width of a foot, mechanism for indicating such measurement, said mechanism including a member with notations thereon progressively arranged indicating different widths of shoe, and with spaced graduations corresponding with such notations and commensurate with determinate changed positions of said side stops, a member having thereon notations progressively arranged indicating different lengths of shoe, with spaced graduations corresponding therewith, and which graduations on the respective members are adapted to have alignment with one another.

when said members are in determinate relative positions, one of said members being fixed with the graduations thereon circularly arranged, the other of said members being 5 circular in form and rotary, with graduations thereon circularly arranged to have co-ordination with the graduations on said fixed member, means for arranging said members whereby the graduations thereon will occupy 10 determinate positions with relation to one another for determinate positions of said side stops, means for simultaneously moving said side stops either toward or away from one another, and means for rotating the 15 rotary one of said members as said side stops are moved with a direction of movement determinate with the direction of movement of said side stops and in an amount equal to the spacing between the graduations thereon as 20 said side stops are moved in an amount equal to a single shoe width.

5. In a foot-measuring device the combination comprising side stops movable toward and away from one another for measuring the 25 width of a foot, mechanism for indicating such measurement, said mechanism including a member with notations thereon progressively arranged indicating different widths of shoe and with spaced graduations corresponding 30 with such notations and commensurate with determinate changed positions of said side stops, a member having thereon notations progressively arranged indicating different lengths of shoe and with spaced graduations 35 corresponding therewith, and which graduations on the respective members are adapted to coincide when said members are in determinate relative positions, means for arranging said members whereby the graduations 40 thereon will occupy determinate positions with relation to one another for determinate positions of said stops and whereby also said members may be movable relatively to one another and the relative positions of the graduations thereon changed, means for simultaneously moving said side stops either toward or away from one another, and means whereby said members may be moved relatively to one another as said side stops are moved with 45 a direction of movement determinate with the direction of movement of said side stops and in an amount equal to the spacing between the graduations on either of said members as said side stops are moved in an amount equal to a single shoe width.

6. In a foot-measuring device, the combination comprising side stops movable toward and away from one another for measuring the width of a foot, mechanism for indicating 50 such measurement, said mechanism including separate members, one fixed and the other movable, the respective members having notations thereon progressively arranged, one bearing notations of shoe lengths, the other notations of shoe widths, each of the respec- 55

tive members bearing also graduations corresponding with its respective notations, and which graduations on the respective members are adapted to have alignment with one another when said members are in determinate 70 relative positions, means for arranging said members whereby the notations and graduations thereon will bear a certain determinate relationship to the different positions occupied by said side stops, means for simultaneously moving said side stops either toward or away from one another, and means for moving the movable one of said members as said side stops are moved with a direction of movement determinate with the direction of 75 movement of said side stops and in an amount equal to the space between the graduations on said movable member as said side stops are moved in an amount equal to a single shoe width whereby any determinate size of shoe in 80 length may be read in terms of width.

7. In a foot-measuring device, the combination comprising a footrest, spaced side stops simultaneously movable over the face of said footrest toward or away from one another to any determinate adjusted position along a common line of travel extending substantially through the ball portion of a foot disposed between said stops, a scale for indicating different sizes of shoes as to width with 90 graduations commensurate with determinate changed positions of said side stops, means for moving said side stops with a determinate degree of movement whereby changed adjusted positions thereof will be commensurate 95 with the graduations on said scale, a movable indicator for said scale indicating width having thereon spaced graduations indicative of sizes of shoes as to length and which graduations are arranged in positions commensurate with determinate adjusted positions of said side stops and the spaces between which graduations are substantially equal to the spaces between the graduations on said scale indicating width, said movable indicator 100 co-operating with said scale indicating width in a manner whereby any one of its graduations as the indicator is moved may traverse the scale indicating width and coincide for purposes of indication with any graduation thereon, and means whereby said indicator will be moved as said side stops are moved in a direction determinate with the direction of movement of said side stops and in such amount that said indicator will move a distance equal to the space between the graduations on the scale indicating width as said side stops are moved in an amount equal to a single shoe width.

8. A foot-measuring device comprising a 105 footrest, spaced heel and toe stops simultaneously movable toward and away from one another to any determinate adjusted position along a common line of travel extending substantially through the longitudinal centre of 110

a foot interposed between said stops, side stops each arranged equidistantly from the line of travel of the heel and toe stops and simultaneously movable toward and away from one another to any determinate adjusted position along a common line of travel extending at right angles to the line of travel of the heel and toe stops with disposition also whereby the side stops will engage the opposite sides of a foot disposed between the heel and toe stops at substantially the ball part of the foot, a scale for indicating different sizes of shoes as to length with graduations thereon commensurate with determinate changed adjusted positions of said heel and toe stops, means for moving said heel and toe stops with a determinate degree of movement whereby the changed adjusted position thereof will be commensurate with the graduations on said scale, means whereby any changed adjusted position of said heel and toe stops will be indicated on said scale, a scale for indicating different sizes of shoes as to width with graduations thereon commensurate with determinate changed positions of said side stops, means for moving said side stops with a determinate degree of movement whereby changed adjusted positions thereof will be commensurate with the graduations on said scale indicating width, a movable indicator for said scale indicating width having thereon spaced graduations indicative of sizes of shoes as to length and which graduations are arranged in positions commensurate with determinate adjusted positions of said side stops and the spaces between which graduations are substantially equal to the spaces between the graduations on said scale indicating width, said movable indicator co-operating with said scale indicating width in a manner whereby any one of its graduations as the indicator is moved may traverse the scale indicating width and coincide for purposes of indication with any graduation thereon, and means whereby said indicator will be moved as said side stops are moved in a direction determinate with the direction of movement of said side stops and in such amount that said indicator will move a distance equal to the space between the graduations on the scale indicating width as said side stops are moved in an amount equal to a single shoe width.

JEREMIAH FITZPATRICK.
